3 Claims. (Cl. 241—171)

Our invention relates to a continuously operating grinding mill of the vibratory type having one or more grinder drums which contain a number of balls or other grinder bodies and which receive the material to be ground through an inlet near one axial end of each drum and discharge the material near the opposite end.

In the known mills of this type, the material is supplied through an inlet opening or duct located above the load, namely the mass of grinder bodies and material, contained in the drum. In such mills, clogging may occur at the inlet because the material, after being charged onto the grinder bodies, is only gradually set in motion and drawn between the grinder bodies.

Since nowadays such grinding mills operate at a relatively high filling degree, amounting for example to about 70% of the cross-sectional area in the drum, the free space remaining above the grinding bodies is rather small and can rapidly become filled with material supplied through the inlet. As soon as the space is filled, the grinding bodies progressively lose their freedom of motion. This also impairs the transportation of the material in the axial direction, thus increasing the amount of clogging and often requiring the material feeder device to be shut off. Since clogging of the grinder drum extremely impedes the throwing motion of the grinder balls, a prolonged period of time is needed under such conditions for running the vibratory mill empty, this being necessary before the mill can be refilled with material to be ground.

It is an object of our invention to eliminate the above-mentioned shortcomings and difficulties encountered with vibratory drum-type grinding mills.

To this end, and in accordance with a feature of our invention, the material supply of a continuously operating vibratory mill is arranged below the drum axis so that the material enters into the grinder drum beneath the operating level of the grinding bodies in the direction of motion performed by the grinding bodies and/or by the material being ground.

According to another feature of our invention, the material supply duct of the feeder device extends from above laterally about part of the drum body and has its inlet opening located in tangential relation to the periphery of the drum body below the longitudinal axis of the drum.

According to another advantageous embodiment of the invention, the material supply duct of the feeder device is mounted laterally of a drum-cover plate at the material-input side of the grinder drum, and the inlet opening extends in the cover plate and is elongated in a direction inclined to the longitudinal center plane of the drum. In this case the supply of material is substantially in the general travel direction of the material being ground in the drum.

According to a further feature of the invention, a removable lid is placed upon the lower end of the supply duct for the material to permit taking specimens of the supplied material out of the inlet duct.

The above-mentioned and other objects, advantages and features of our invention, said features being set forth with particularity in the claims annexed hereto, will be apparent from and will be described in, the fol-

2

lowing with reference to embodiments of vibratory grinding mills according to the invention illustrated by way of example on the accompanying drawings in which:

FIG. 1 is a lateral view of a vibratory mill comprising two grinder drums, the supporting and mounting structure being omitted.

FIG. 2 is a longitudinal section through the vertical center plane of part of the upper drum near the material-inlet side of the mill shown in FIG. 1.

FIG. 3 is a part-sectional front view upon the grinder drum according to FIG. 2.

FIG. 4 is a front view onto the inlet side of a grinder drum according to another embodiment of the invention.

FIG. 5 is a lateral view of part of the grinder drum shown in FIG. 4; and

FIG. 6 shows schematically a complete vibratory mill according to FIGS. 1, 2 and 3.

The vibratory mill shown in FIGS. 1, 2, 3 and 6 comprises two cylindrical grinder drums 1 and 2, which are horizontally arranged one above the other in symmetrical relation to the drive shaft 10 of the machine. The upper drum 1 is provided with an inlet duct 3 for supplying the material 12 to be ground. Both drums contain a quantity of grinder bodies, such as hard balls, which during vibration are subjected to throwing motion in order to grind the material. The material passes from the inlet side of the upper drum 1 to the opposite side and thence through a corrugated hose 8 into the lower grinder drum 2. In drum 2 the material is subjected to further grinding while traveling to the left and through a screening partition to an outlet 9.

The two drums 1 and 2 are rigidly connected with each other by two bridge members 15 which carry respective bearings 16 for the machine shaft 10. The bridge members are rigidly joined with two lateral supports 6 seated on respective spring members 18 preferably consisting of rubber bodies. The springs 18 are supported on rigid standards 19 secured to the foundation of the plant. By virtue of this mounting, the rigid assembly comprising the two grinder drums is capable of swinging motion in transversal planes parallel to the plane of illustration in FIGS. 3 and 6. The shaft 10 carries unbalance weights 11 and is driven from a stationarily mounted motor (not shown). Due to the rotation of the unbalance weights 11, the drum structure receives pulses which cause it to perform a substantially circulating vibration in planes transverse to the drum axes. It will be understood that the particular unbalance drive is not essential to the invention proper and may be substituted by other vibratory drives such as those operating with a rotating crank coupled with the vibratory drum system by means of a spring.

The grinder balls in each drum occupy only part of the internal drum space and thus approximately define a load level in each drum. During operation of the mill, the grinder balls in each drum perform a throwing motion thus imposing a comminuting action by impact and friction upon the material to be ground.

While in the known vibratory drum or tube mills, the feeder conduit is joined with the top of the drum to supply the material upon the just-mentioned level, the duct 3 in the vibratory mill according to FIGS. 1 to 3 and 6 extends from above laterally about part of the drum periphery so that the feeder inlet opening of the drum, through which the duct 3 communicates with the interior of the drum, extends tangentially to the drum periphery below the longitudinal axis of the drum. This permits supplying the material in the throw direction of the grinding bodies or balls and thereby affords a continuous supply of material without danger of clogging the drum.

It is of advantage to provide the lower end of the supply duct 3 with a cover or lid 6 which can be turned to

open position or fully removed so that specimens of the material to be ground can be taken out at any time from the material passing through duct 3 and into the drum.

In the embodiment according to FIGS. 4 and 5, the duct 4 of the material feeder device is arranged beside the axial end, namely in front of the cover plate 7 at the feeder side of the drum 1, and the inlet opening 4' is located in the cover plate 7 and is elongated in an inclined direction with respect to the longitudinal vertical center plane of the drum. In this case the material enters into the drum generally in the traveling direction of the material 12 being ground, that is in the direction from the cover plate 7 at the feeder side to the opposite end of the drum where the drum outlet and the corrugated hose 8 is located.

The supply duct 4 receives the material from a vertical feeder conduit 5 which is rigidly fastened, for example by brackets or flanges (not shown), to the cover plate 7 of the drum. The lower end of the feeder conduit 5 is closed by a cover 6 which can be turned open or removed in order to permit specimens of the material to be taken from time to time.

As is the case with a tangential supply of the vibratory mill with material to be ground (FIGS. 1 to 3 and 6), the lateral supply through an opening in the cover plate 7 of the drum (FIGS. 4, 5) also affords a continuous supply of material without danger of clogging the mill.

The tangential as well as the axially lateral supply of the material to be ground also offer the advantage of feeding the material into the mill below the level of the grinding bodies, namely either in the direction of motion of the grinder bodies (tangential supply) or in the travel direction of the material being ground (axially lateral supply of the material). In both cases, exemplified by the above-described embodiments of the invention, the material to be ground enters only into the interspaces between the grinding bodies or balls as they pass by the inlet opening. Thus the material is promptly removed from the inlet opening in a manner that virtually amounts to a dosage-forming action. This promotes the prevention of clogging.

By virtue of the tangential or lateral supply of the material, this material can be fed into the drum at the side at which the grinder bodies perform a downward motion. This secures a continuous feeding action upon the material to be ground, thereby also contributing to reliable prevention of clogging.

To those skilled in the art, it will be obvious upon a study of this disclosure that vibratory grinding mills according to the invention can be modified in various respects and can be given embodiments other than particularly illustrated and described herein, without departing from the essential features of our invention and within the scope of the claims annexed hereto.

We claim:

1. A continuously operable vibratory grinding mill, comprising at least one vibrantly mounted grinder drum whose axis extends substantially horizontally and which contains grinder bodies up to an approximate level, said drum having near one end a material inlet opening located substantially below said level, and having an outlet near the other end, vibratory drive means connected

with said drum for vibrating said drum whereby motion relative to the drum is imparted to said grinder bodies in a direction transverse to the drum axis and the material is caused to travel in the direction from said inlet opening to said outlet, and a duct for supplying material communicating with said drum through said inlet opening below said level and extending in one of said two directions at said opening, said material supply duct having a downwardly extending portion ahead of said inlet opening, and a removable cover on said duct portion for taking specimens of the material being supplied.

2. A continuously operable vibratory grinding mill, comprising at least one elongated grinder drum whose axis extends substantially horizontally, said drum having an elastic mounting for circulatory transverse vibration and containing grinder bodies partially filling the drum, said drum having near one end an inlet opening for material to be ground and having an outlet near the other end, vibratory drive means connected with said drum for vibrating said drum whereby motion relative to the drum is imparted to said grinder bodies in a direction transverse to the drum axis and the material is caused to travel in the direction from said inlet opening to said outlet, said inlet opening being located substantially below the drum axis, and a duct for supplying material communicating with said drum through said inlet opening and extending from above laterally of the drum and thence substantially in a tangential direction to said inlet opening for feeding the material to the drum in the moving direction of said bodies at said inlet opening.

3. A continuously operable vibratory grinding mill, comprising at least one vibrantly mounted grinder drum whose axis extends substantially horizontally and which contains grinder bodies partially filling the drum, said drum having a cover plate on one axial end and having in said cover plate an inlet opening for material to be ground and having an outlet near the other end, vibratory drive means connected with said drum for vibrating said drum whereby motion relative to the drum is imparted to said grinder bodies in a direction transverse to the drum axis and the material is caused to travel in the direction from said inlet opening to said outlet, said inlet opening being located substantially below the drum axis and extending in a direction inclined to the vertical center plane of the drum and a duct for supplying material communicating with said drum through said inlet opening and extending from above axially beside said cover plate, whereby the material enters into the drum substantially in the direction of travel of the material through the drum.
